ALEXANDER SCHWEITZER AND FRITZ HAUFF, OF STUTTGART, GERMANY.

PROCESS OF MANUFACTURING NITROGEN COMPOUNDS.

1,037,061.

Specification of Letters Patent. Patented Aug. 27, 1912.

Application filed March 12, 1912. Serial No. 683,198.

To all whom it may concern:

Be it known that we, ALEXANDER SCHWEITZER and FRITZ HAUFF, citizens of the German Empire, residing at Stuttgart, Germany, have invented certain new and useful Improvements in Processes of Manufacturing Nitrogen Compounds, of which the following is a specification.

Our invention relates to the manufacture 10 of nitrogen compounds by electrically heating quantities of such substances as compounds of the alkalis or alkali earths in the presence of carbon and in an atmosphere of nitrogen.

15 Many processes of the above kind for the fixation of nitrogen, utilizing the hydrates, oxids, or carbonates of the alkali or alkali earth metals are known and patented, but when carried out on an industrial scale these 20 previous processes have been attended with great drawbacks. It has been found difficult and costly to attain the high temperature required for the reaction and the retorts in which the reaction is carried out are seriously attacked owing to the basic character 25 of the charge.

The object of the present invention is to overcome the drawbacks hitherto experienced and to secure a continuous operation.

30 The invention consists substantially in that the reaction charge, *i. e.* a mixture containing alkali or alkali earth metal compounds and carbon, is continuously guided through an electrically heated zone in a 35 form allowing conductance of electric current and permeable to gas when heated, in a direction opposing a current of nitrogen containing gas, the charge constituting an electrical resistance in the heating zone.

40 To bring the charge to a form in which it can be used as a resistance for conducting the electric current the alkali or earth alkali compounds along with fluxes when required and coal are finely powdered and

45 mixed and subjected to a coking process, preferably after the mixture has been formed into briquets. The mixture is thus in the form of lumps and in comparison with the uncoked mixture possesses increased 50 electrical conductivity and a porous gas permeable structure which offers a large surface very desirable in the treatment in a current of gas, which porous condition is not lost when the briquets are subjected to the heat. 55 Utilizing for instance a mixture containing equal proportions of barium carbonate and

coke there is obtained a coke which is extremely suitable for forming the nitrogen compounds in an electric heating zone, and of which the composition corresponds with 60 a mixture of about 60% of barium carbonate and 40% of coke.

The continuous heating of any desired amount of the material formed in the above described manner, for the purpose of fixation of nitrogen, may be preferably carried out in a cupola furnace of the type illustrated in the accompanying drawings. At about half the height of the shaft *e* of the furnace electrodes *b* pass transversely 65 through the walls *a* of the shaft and project into the charge space. To insure that substantially only that part of the charge lying between the electrodes participates in the conduction of the current, the shaft is divided by partitions *c* of non-conducting material arranged both above and below the electrodes and extending close to the zone between the same. The electrodes may be 70 of carbon, graphite or the like but are preferably of chilled metal. The removal of the material takes place on the hearth of the furnace and fresh material is fed in to a corresponding extent at the top. The nitrogen or gas containing nitrogen is blown in 75 at the hearth through pipes *d* and passes over the charge which is falling down through the shaft. The waste gases leave 80 the furnace at *f*.

The furnace illustrated in the drawing is 85 provided with two electrodes *b* but there is no reason why a larger number should not be employed. With polyphase currents for example three electrodes may be used, the number of the insulating partitions *c* being 90 then preferably such that there is one partition in the shaft at right angles to the main direction of each current flowing through the charge.

What we claim is:

1. The process of manufacturing nitrogen compounds consisting in continually guiding a mixture containing carbon and a compound of an alkali or alkali earth metal through an electrically heated zone, said 105 mixture being permeable to gas and possessing electrical conductivity, and itself serving as a resistance for the generation of heat, preserving the permeability of the mixture during the heating operation, and passing 110 a current of nitrogen containing gas through the material while in the heated zone.

2. The process of manufacturing nitrogen compounds consisting in continually guiding a mixture containing carbon and an unfused compound of an alkali or alkali earth metal through an electrically heated zone, said mixture possessing electrical conductivity and itself serving as a resistance for the generation of heat, controlling such heat so as to keep the temperature below the fusing point, and passing a current of nitrogen containing gas through the material while in such electrically heated zone.

3. The process of manufacturing nitrogen compounds which consists in forming a porous mixture of carbon and a compound of an alkali or alkali earth metal, coking such mixture without fusion, guiding such coked mixture through an electrically heated zone, the mixture itself serving as an electrical conductor and resistance for the generation of heat, controlling such heat to prevent fusion, thereby preserving the permeability of the material, and passing a current of nitrogen containing gas through the mixture.

4. Process of manufacturing nitrogen compounds consisting in continually guiding a coked mixture containing alkali or alkali earth metal compounds and carbon through an electrically heated zone guiding a current of nitrogen containing gas through said mixture in said electrically heated zone and using said mixture as an electrical resistance in said heating zone and preventing the heating current from materially affecting the bulk of mixture outside the heating zone.

5. Process of manufacturing nitrogen compounds consisting in continually guiding a mixture containing alkali or alkali earth metal compounds and carbon through a shaft provided with electrodes projecting thereinto, using the mixture within the shaft between the electrodes as heating resistance in an electric current limiting the active zone of current transmission to that portion of the mixture lying substantially in the plane of the electrodes and transmitting a current of nitrogen containing gas through said shaft and mixture therein positioned between the electrodes.

6. Process of manufacturing nitrogen compounds consisting in continually guiding a coked mixture containing alkali or alkali earth metal compounds and carbon through a shaft provided with electrodes projecting thereinto, using the mixture within the shaft between the electrodes as heating resistance in an electric current limiting the active zone of current transmission to that portion of the mixture lying substantially in the plane of the electrodes and transmitting a current of nitrogen containing gas through said shaft and mixture therein in a direction opposite the direction of movement of the mixture through the shaft.

In testimony whereof, we affix our signatures in presence of two witnesses.

ALEXANDER SCHWEITZER.
FRITZ HAUFF.
